US00D798346S

(12) **United States Design Patent** (10) **Patent No.:** **US D798,346 S**
(45) **Date of Patent:** **** Sep. 26, 2017**

(54) **ROTARY DAMPER**

- (71) Applicants: **James E. Pearson**, Downers Grove, IL (US); **Paul H. Tuma**, Lombard, IL (US)
- (72) Inventors: **James E. Pearson**, Downers Grove, IL (US); **Paul H. Tuma**, Lombard, IL (US)
- (73) Assignee: **Robertshaw Controls Company**, Itasca, IL (US)
- (**) Term: **15 Years**
- (21) Appl. No.: **29/566,186**
- (22) Filed: **May 27, 2016**

Related U.S. Application Data

- (63) Continuation of application No. 15/015,224, filed on Feb. 4, 2016.
- (51) **LOC (10) Cl.** **15-07**
- (52) **U.S. Cl.** **USPC D15/89**
- (58) **Field of Classification Search**

(74) *Attorney, Agent, or Firm* — Reinhart Boerner Van Deuren P.C.

(57) **CLAIM**

We claim the ornamental design for the rotary damper, as shown and described.

DESCRIPTION

FIG. 1 is a bottom perspective view of the rotary damper;
FIG. 2 is a top perspective view thereof;
FIG. 3 is a top perspective view thereof that has been rotated 180° from that shown in FIG. 2;
FIG. 4 is a side view thereof;
FIG. 5 is a top view thereof;
FIG. 6 is a side view thereof showing the side that is 90° clockwise from that shown in FIG. 4;
FIG. 7 is a bottom view thereof;
FIG. 8 is a side view thereof showing the side opposite that shown in FIG. 6; and,
FIG. 9 is a side view thereof showing the side opposite that shown in FIG. 4.
The dashed lines in the drawings depict unclaimed environmental subject matter.
